LOCKING DEVICE

Arvid H. Nero, West Hartford, Conn., assignor to
 The Arrow-Hart & Hegeman Electric Company,
 Hartford, Conn., a corporation of Connecticut

Application September 29, 1930, Serial No. 485,273

1 Claim. (Cl. 173—323)

It is often necessary, when using electrical devices which derive their current from an electrical outlet or receptacle which is situated in the base board or in the wall of a room to carry the 5 electrical device about. In moving the electrical device, a strain is often put on the cord which is connected to the attachment plug cap and often times this strain is sufficient to disengage the cap from the receptacle thereby breaking the electrical connection.

This invention relates to devices for securing the members of a separable electric fitting together, such as is described and claimed broadly in my copending application Serial No. 330,050, 15 filed January 3rd, 1929 patented August 30, 1932, No. 1,874,334. My present invention relates more particularly to a device which is adapted to cooperate with the flush plate of an electric receptacle and to hold an attachment plug cap in circuit- 20 closing engagement with the receptacle.

It is an object of my invention to provide a simple and efficient locking device which can be inexpensively made and which will act to hold the attachment plug and the receptacle together 25 until the locking device is released manually.

Referring to the drawing:—

Figure 1 is a perspective view of a flush plate and receptacle with which is associated my new locking device. This figure also shows in perspective an attachment plug cap in position to be inserted in the receptacle.

Figure 2 is a side elevation view of the construction shown in Figure 1 but with the attachment plug cap inserted in the receptacle and secured by my new locking device.

Figure 3 is a mid-section view of my locking device.

Figures 4 and 5 are perspective views of the two parts of the locking device.

Referring to the drawing, 10 indicates a conventional flush plate to which is secured by screws 11 a conventional receptacle 12 in which are contact apertures 13. An attachment plug cap 14, 45 having contact blades 15 which are adapted to be inserted in the apertures 13 to complete the electric circuit, has a strain relief fitting like that shown in my Patent No. 1,874,334. This fitting comprises a ring 18 adapted to be slipped over the 50 working end of the attachment plug cap 14 and to rest against an annular shoulder 20 formed on the cap. Extending from opposite sides of an outwardly offset flange 22 on the ring 18 are arms 24, the free ends of which are shaped to form 55 gripping jaws having laterally projecting lugs in

which are apertures to receive clamping screws to clamp the jaws together and grip the cable C. For a purpose which will presently appear, two notches 26 are formed in the flange 22 in diametrically opposed positions.

The locking device which I employ comprises relatively rotatable outer and inner ring shaped members 28 and 32 which may be stamped from sheet metal and which have the same inside diameter but the member 28 has a greater outside 60 diameter. The member 28 has two lateral extensions 30 which are apertured to permit the insertion of the screws 11 in order that the member may be secured to the flush plate 10 and receptacle 12 by the same screws that secure the plate 70 and receptacle together. The inner periphery of the member 28 is slightly raised or offset from the body of the ring to permit the member 32 which is approximately of the same size as the offset portion 31, to lie beneath the member 28 75 with the lower surfaces of both members in the same plane.

Projecting up from the inside of the member 32 are arms 34 having bent over ends 36 for the purpose of engaging flange 22 of the strain relief fitting in order to hold the cap 14 in engagement with the receptacle when all the parts are assembled. These arms also serve to hold the members 28 and 32 together during shipment and at other times when they are not secured to a 85 face plate. For this latter purpose the mid portion of the arms are bent backwardly over the ring portion of the member 32. Thus when the members 28 are together, an effort to separate them will cause the mid-portion of the arms to 90 engage the offset portion 31 of the member 28 thereby preventing their separation. In order to assemble and disassemble the member 32 and the member 28 without distorting the arms 34 a notch 95 38 is cut in the offset portion 31 of the member 28 to receive one of the arms 34. The notch is of such depth that when one of the arms 34 lies in it the other arm will just clear the inner periphery of the member 28 as the members 28 and 32 are pushed together.

Now the locking device may be secured on the face plate 10 and the member 32 may be rotated relative to the ring 28 until the lugs 34 are in position to register with the notches 26 of the attachment plug cap at the moment when the prongs 15 of the cap are being inserted into apertures 13 of the receptacle. As soon as the prongs 15 have been pushed home and the circuit completed between the receptacle and the attachment 110

plug cap, the member 32 may be rotated by means of the lugs 34 and the inwardly turned ends 36 of these lugs will overlie the flange 22, thus preventing the cap from being pulled out of engagement with the receptacle.

Thus it will be seen that I have provided a simple locking device which may be inexpensively manufactured in large quantities from sheet metal by means of a die press. Obviously many modifications within the scope of this invention will occur to those skilled in the art and therefore I do not limit myself to the specific embodiment shown.

What I claim is:—

As an article of manufacture a ring shaped member having an offset portion adjacent its inner periphery and having apertured extensions, and a second ring shaped member cooperating with said offset portion and having upstanding bent arms which maintain said members in engagement, said arms having turned over end portions, said offset portion having a notch adapted to cooperate with one or the other of said arms whereby said members may be readily assembled or separated.
